SIGNAL DEVICE FOR VEHICLES

Application filed January 11, 1930. Serial No. 420,098.

The invention relates to a signal device for use on a vehicle to indicate to persons not on the vehicle intended changes in the direction or rate of motion of the vehicle.

5 An object of the invention is to provide for a significant viewing of a single signal element from a maximum number of directions with respect to the vehicle which carries it.

10 A more specific object of the invention is to provide a signal means for direct viewing by a person positioned laterally of the path of the vehicle whereby said person may be positively advised of an intended turn of the vehicle to his side of said path.

15 Another object of the invention is to provide a particularly simple and improved structure for a signal device of the class described.

20 The invention possesses other objects and features of advantage, some of which, with the foregoing, will be set forth or be apparent in the following description of one embodiment of the invention which is illustrated in the accompanying drawings, in which:

25 Figure 1 is a rear end view of a typical form of the device.

Figure 2 is an axial and vertical section of the structure shown, a portion of a transparent tubular element thereof being broken away to show certain parts therewithin.

30 Figure 3 is a transverse section taken as at 3—3 in Figure 2.

35 As particularly illustrated, the present invention is embodied in a structure primarily comprising an assembly of three transparent tubular members 5, 6 and 7 fixed in mutually parallel relation between transparent plate members 8 and 9 whereby to define cavities in which to house electric lamps 11 or other sources of light. Each of the transparent lamp housings thus cooperatively provided by the tubes and plates is arranged to function as a signal when a lamp is lit therein, the signals thus provided for being appropriately differentiated whereby said signals may be of different significances, each of said signals being visible laterally of the tubular members, as well as axially thereof, and from opposite directions. Conveniently, and as

shown, the tubular members 5, 6 and 7 are formed as sections of circular tubing having the same lengths whereby the plates 8 and 9 are parallelly related in the assembly.

Means are provided whereby the plates 8 and 9 are utilized as clamp members for securing the tube members in their relatively fixed relation to each other. Accordingly, and as shown, the opposed, and inner, plate faces are recessed to receive the tube ends in fitted engagement therewith whereby lateral displacements of the tubes from their positions in the assembly is positively prevented. Preferably, the tube members are tangentially engaged in the assembly whereby they define a prismatical space 12 between them and between the plates 8 and 9. Each of the latter plates is perforated axially of the space 12 to permit the engagement of a clamp bolt 13 therethrough and through said space, the head of said bolt engaging the outer face of the plate 8 while the threaded bolt end threadedly engages in a disc member 14 which in turn engages the outer face of the plate 9; in this manner, an assembly is provided in which the tubes and plates are rigidly related to provide a multiple-signal unit. Considering the bolt and disc as a clamp means, the disc is understood to comprise a nut for the bolt.

The lamps 11, it will now be noted, are mounted in sockets 15 which are in turn carried on supporting arms 16 extending inwardly from the inner face of the disc 14 and within the various tubes. Preferably, and as shown, the arms 16 comprise the segments of a longitudinally slit cylindrical tube 17 extending axially from the disc 14 and with each slit 18 between the arms 16 thereof receiving abutting wall portions of the transparent tubes, the relation being particularly brought out in Figure 3. The bolt-receiving perforation in plate 9, it is noted, is made large enough to receive the tube 17, and the cylindric lateral curvature of the arms 16 stiffens them to a required degree for supporting the sockets 15 in their places, said sockets extending radially of the bolt axis. The specific socket and lamp structure is immaterial to the present invention;

as shown, a usual bayonet connection is provided for mounting the lamps in their sockets.

The concavities of the laterally curved 5 arms 16 cooperate with the opposed wall portions of the transparent tubes to define conduits for the necessary wires 19 to the sockets 15, and the disc 14 is perforated in line with said conduits to provide for the extension of the wires 19 therethrough. A supporting bracket 21 is provided at the outer side of the disc 14, said bracket in the present 10 instance comprising a tubular portion 22 extending radially from the disc 14 and a flat 15 and perforated end portion 23 for fixing to a supporting portion of a vehicle (not shown). The tubular portion 22 is arranged to receive the wires 19 therethrough and is shown as integral with the disc 14. It is to be understood, however, that the specific form of 20 bracket which carries the signal assembly through the disc 14 is generally immaterial to the present invention. Preferably, the tube 17, disc 14, and bracket 21 are metallic 25 whereby they provide a common conductor to the various lamps 11 and but a single wire 19 is required from each lamp socket for providing operatively independent circuits for the various lamps, said circuits each including a switch (not shown) and a source of electrical power (not shown).

The various signals provided by the assembly are arranged to be primarily differentiated in terms of color, and the device may 35 be used with equal readiness on land or water or air-borne vehicles. For land-borne and dirigible vehicles such as automobiles, the disposition is preferably that shown wherein the tubes 5, 6 and 7 are horizontally 40 disposed and the end plates 8 and 9 are arranged to respectively face rearwardly and forwardly of the line of movement of the vehicle. Furthermore, two of the tubes are at the same level, the third tube being 45 either above or below said level; as shown, the tube 5 is uppermost. The portions of the plates 8 and 9 beyond the tubes are shaped as may be desired; as shown, these plates closely follow the sectional outline of 50 the assembly of the three tubes whereby the outline of a three-leaf clover is suggested. For effecting the aforesaid color differentiation in the signal, the tubes and end plates may be of different and appropriate colors.

55 As shown, the transparent tubes 5, 6 and 7 are respectively colored red, orange and green, said tubes being of glass or some other sufficiently stiff transparent material. Since to follow out the aforesaid color scheme, 60 different portions of the plates 8 and 9 would be differently colored, it will generally be preferable to form these plates of uncolored glass, or the like, and to interpose appropriately colored discs 25 between the tube 65 ends and their seats on the plates, the effect

being that of coloring the plates themselves. If desired, symbols indicating the significance of the different signals may be provided on the plates and/or tubes; as shown, symbols 26 are defined on the plates 8 and 9 opposite the ends of the different tubes whereby a person viewing the device from the front or rear of the vehicle is advised that the red upper signal indicates a stop or slowing down of the vehicle, the orange left-side signal indicates a left turn for the vehicle, and the green right-side signal indicates a right turn for the vehicle. 70 75

While the present assembly is such as to be generally watertight against rain, drainage for any moisture which may get into the tubes is preferably provided for. As shown at 27 in Figure 2, the lower rim portion of the color disc 25 of the tube 5 and at the plate 8 is notched to provide a drainage passage. Drainage from the lower signal tubes is provided by notching the lower discs at 28 and providing channels 29 in the plate faces at the ends of the tubes 6 and 7, this feature being shown in Figure 3. 80 85 90

The present device is understood to be applicable to air-borne vehicles, a red signal being then given to indicate an upward or downward movement of the vehicle in accordance with the direction from which the vehicle is viewed. The provision of the right and left-turn signals for lateral viewing is seen to be particularly valuable for advising persons positioned laterally of a vehicle as to the intentions of the driver of the 100 vehicle respecting his direction of progress, the usual hand signals being generally least visible from a lateral direction and crossing collisions frequently resulting from the latter fact. To prevent an illumination of one signal of the device by the light from another, the interiors of the various tubes 5, 6 and 7, are partially covered with a coating 31 of an opaque paint or other covering material extending around their generally inner 105 portions whereby the light from a given lamp 11 will illuminate but the one signal which it is intended to illuminate. 110 115

From the foregoing description taken in connection with the accompanying drawings, the advantages of the construction and method of operation will be readily understood by those skilled in the art to which the invention appertains, and while we have described the principle of operation, together 120 with the device which we now consider to be the best embodiment thereof, we desire to have it understood that the device shown is merely illustrative, and that such changes may be made, when desired, as fall within the scope of the appended claim. 125

Having thus described our invention, we claim as new and desire to secure by Letters Patent of the United States the following:

In a signal device of the class described, a 130

plurality of independent and like tubular elements arranged in symmetric and parallel relation to a common axis, plate elements of transparent material engaging corresponding ends of said tubular elements for retaining the same in said relation, mutually engaged bolt and nut members cooperative with said plate elements to effect a clamped engagement of said tubular elements between them, arms extending axially from said nut member and within said tubular elements, sources of light mounted on said arms within said tubular elements, and a bracket carrying said nut member.

15 In testimony whereof we affix our signatures.
